[57] ABSTRACT

Valve assembly for use in valved musical instruments comprises a lug member secured to the valve and movably fitted in the groove longitudinally extending on the inner wall of the valve outer casing, in order to prevent the valve from turning in the casing. The lug member has a pair of projections separated by a slit and also has a screw-receiving bore interconnecting with the slit. Screwing of a screw having a flaring side surface into the bore widens the bore and slit of the lug member, that is, increases the distance between the pair of projections, thereby attaining a snug fitting of the lug member in the groove.

FIG. 1

FIG. 2

FIG. 3

FIG. 4

FIG. 5**FIG. 6**# VALVE ASSEMBLY OF VALVED WIND MUSICAL INSTRUMENT

BACKGROUND OF THE INVENTION

a. Field of the Invention

The present invention is concerned with a valve assembly for a valved wind musical instrument such as trumpet, and more particularly, it relates to an improvement in the structure of a specific member of this valve assembly to inhibit undesirable turning of the piston valve of the valve means of the assembly which is caused to make sliding movements within a tubular outer casing of said valve means.

b. Description of the Prior Art

In musical instruments classified as valved wind musical instruments such as trumpets, there are provided piston valve assemblies in order to vary the effective length of the air column of the instrument and thereby to control the tone pitches. Such a valve assembly has a piston valve making the reciprocal sliding movements within its outer casing, and, in order to ensure the correct registering of air-passage openings formed through the piston valve with the holes of the tubes provided on the valve casing, the assembly is further equipped with special means for inhibiting the turning of the piston valve of the valve assembly during the operation of the valve.

This special means comprises a lug member fastened by a screw to a piston rod-connecting block which is positioned in the upper part of the piston valve. The lug member is received, for engagement, in a lug-receiving groove which is formed longitudinally in the inner wall of the tubular outer casing of the valve assembly to ensure that the valve body will not turn during its vertical reciprocal movements in the tubular outer casing.

In manufacturing the lug member and its receiving groove of the tubular outer casing, it is essential that there exists no undesirable play or space between the lug member and its receiving groove. This is because of the consideration that, in case there is a substantive space between the lug member and the groove for receiving this lug member, there will develop clattering noises during the operation of the valve. These clattering noises not only do not contribute favorably to the effect of the music being played, but also will destroy the feeling or mode of the player. Especially, during the recording of a music being played, these unnecessary noises will be caught by the microphone.

In order to eliminate the unnecessary play between the lug member and the groove for receiving it, therefore, it has been the practice in the past to strike the lug member with a hammer to increase the breadth of the groove-engaging portion of the lug member to thereby adjust this breadth so that the lug member will fit snugly in the groove.

Such an adjustment intended for the play-eliminating operation, however, takes a considerable length of time, and moreover such an operation requires a trained skill of the operator. Furthermore, the striking at the lug member will unavoidably leave scars on the surfaces of the lug member and spoiles the appearance of the lug member itself. In addition, when there develops such play again between the lug member and groove due to wear of the lug member during the extended use of the valve, it is now almost impossible to eliminate this play again by striking the once struck lug member.

SUMMARY OF THE INVENTION

It is, therefore, the object of the present invention to solve the aforesaid problems of the valve assembly and to eliminate the aforesaid inconveniences of the prior art.

Another object of the present invention is to provide valve assembly having a unique lug member which has a bifurcated groove-engaging portion which is capable of varying the gap between the abutting arms of the bifurcated portion of the lug member so as to be broadened to thereby enable the engaging portion of the lug member to be set as desired to desirably fit in the guide-receiving groove of the outer tubular casing of the piston valve.

BRIEF DESCRIPTION OF THE DRAWINGS

FIG. 1 is an explanatory illustration of valve assemblies as a part of a wind musical instrument.

FIG. 2 is an explanatory illustration of a valve assembly provided with a lug member according to an embodiment of the present invention.

FIG. 3 is an enlarged plan view of the lug member shown in FIG. 2, taken along the line III — III in FIG. 2.

FIG. 4 is a sectional view taken along the line IV — IV in FIG. 3.

FIG. 5 is an exploded perspective view of the lug member and its related parts shown in FIG. 2.

FIG. 6 is an explanatory illustration of a valve assembly according to another embodiment of the present invention.

DETAILED DESCRIPTION OF THE PREFERRED EMBODIMENT

Hereunder will be described an embodiment of the present invention by referring to the accompanying drawings.

FIG. 1 shows a general view of valve assemblies A which are connected to a wind musical instrument such as trumpet. In FIG. 2 is given an explanatory illustration of a valve assembly A according to the present invention, which is provided with a special means for preventing a piston valve from turning within the valve casing. In FIGS. 1 and 2, reference numeral 1 represents a tubular outer casing of a valve assembly. A piston valve 3 is slidably inserted in the tubular outer casing 1, and a coiled compression spring 2 is located between the lower part of the piston valve body 3 and the bottom of the outer casing 1 to normally urge this piston valve 3 and, accordingly, the piston rod, toward the top pressing button 6 and to thereby permit the longitudinal reciprocal sliding movements of the piston valve 3.

The tubular outer casing 1 may be made of, for example, brass. The piston valve 3 may be made of, for example, nickel-plated brass.

To the top of the piston 3 is secured a special means for preventing the valve 3 from turning in the casing 1. This special means comprises a disk-like block 4. A piston rod 5 is secured to this block 4 to extend from the central axis of this block 4. A button 6 is secured to the top of said piston rod 5 to be pressed upon by a finger of the instrument player. As shown in FIGS. 3 to 5, the block 4 is provided, locally in its peripheral part, with a recessed nest 7 of a generally U-shape in configuration which opens in the lateral peripheral direction of

the block 4. Within this recessed nest 7 is received a valve-turning preventive member or lug member 8 for inhibiting the turning of the valve 3 as will be described later in further detail. This lug member 8 may be made of, for example, nickel silver, brass or plastic.

The lug member 8 is of an outer configuration of a generally U-shape when viewed from above or bottom thereof. A bore 8a is formed through the center of the arcuate U-shape of the member 8. This lug member 8 has, in its one end face, a funnel-like outwardly flaring opening 8b which joins said bore 8a at its central portion.

The front end face 8c of this member 8 is formed to have an arcuate shape when viewed from above or bottom thereof, with a curvature substantially conforming to the curvature of the inner wall of the outer casing 1 so as to be complementary in shape to the inner wall of the outer casing. A pair of opposing separate projections 8d and 8d is provided to extend from the central portion of the front end face 8c to provide between these projections a slit 8e which extends from the front end of these projections and joins the central axis of the bore 8a.

The lug member 8 having the aforesaid structure is placed in the nest 7 of the block 4 with the funnel-like flaring opening 8b exposed and located away from the bottom of the nest 7. Numeral 9 represents a flush-headed screw having a tapered side surface profile with a progressively reducing diameter as it goes from the head top toward the shank of this screw. By screwing this flush-headed screw 9, through the flaring opening 8b and the bore 8a of the member 8, into a threaded hole 7a which is formed through the block 4 of the nest 7, the lug member 8 is secured to this block 4, and at the same time by forcing the tapered side 9a of the flush-headed screw 9 to progressively engage the surface of the tapered opening 8b of the member 8, the gap of the slit 8e formed between the abutting arms 8d and 8d can be varied to widen this gap.

The bifurcated end portion of the member 8 or in other words that portion of the member 8 having the slit 8e desirably has such an elasticity as will act to urge the projections 8d and 8d toward each other to narrow the gap d of the slit 8e. It will be understood that by progressively screwing the flush-headed screw 9 into the bore 8a, the gap of the slit 8e will be progressively widened against the above-said slit-narrowing elastic force of the bifurcated end portion of the member 8. Therefore, as this screw 9 is loosened progressively therefrom and as it is removed eventually, the slit 8e will resume its initial narrow gap due to the elastic restoring force of the bifurcated end portion. Such an arrangement of the end portion of the member 8 will facilitate easy adjustment of the positions to be assumed by the projections 8d and 8d.

The above-stated lug member 8 is arranged so that its outwardly flaring (tapered) opening 8b is to be associated with the tapered side 9a of the flush-headed screw 9. It will be understood by those skilled in the art, however, that the member 8 need not have the funnel-like outwardly flaring opening 8b in order to attain the purpose of widening the gap of the slit 8e. Instead, the member 8 may have only the central bore 8a with a parallel straight inner wall face joining the slit 8e. The screw 9 having a tapered head portion will act to widen this slit 8e as this screw is screwed progressively into the bore 8a.

Locally in the external threaded portion of the flush-headed screw 9 is embedded a resinous member 10 for preventing the loosening of the screw 9 after the latter has been screwed, through the lug member, into the block. This member 10 is intended to inhibit the occurrence of loosening of the screw due to vibrations during the frequent manipulation of the piston valve by the player of the instrument.

Also, on the inner wall face of the outer casing 1 is formed a lug member-receiving groove 1a which extends along the axial direction of the outer casing 1. The pair of projections 8d and 8d of the member 8 are inserted in the lug member-receiving groove 1a for slideable engagement therewith, whereby the piston valve 3 can be guided longitudinally along the inner wall of this casing within the outer casing 1 without causing the turning of the valve 3.

As such, let us now assume that the flush-headed screw 9 is tightened progressively by a screw-driver or like means. Whereupon, the stress which is developed at the tapered face 9a of the flush-headed screw 9 acts upon the surface of the tapered opening 8b of the lug member 8 in such a way that the tapered face 9a of the flush-headed screw 9 slides forcibly downwardly into the tapered opening 8b of the lug member 8 while broadening the diameter of this tapered opening 8b. Owing to the resulting broadening action of the tapered opening 8b, the gap d of the slit 8e of the member 8 is widened, with the result that the overall distance between the outer corners at the front ends of the two projections 8d and 8d is increased.

As such, the minute adjustment of this overall distance between the outer corners of the projections 8d and 8d of the member 8 almost up to the full margins of the lug member-receiving groove 1a by turning the flush-headed screw 9 so as to most desirably allow the sliding movements of the member 8 in the groove enables the elimination of the unnecessary play between the lug member 8 and the lug member-receiving groove 1a.

The above-mentioned embodiment has been shown as one having the spring 2 which is arranged at the bottom of the piston valve 3. According to another embodiment of the invention, the spring 2 may be provided on top of the valve 3 and between the top of the casing 1 and the spring receiving plate 11, and surrounding a portion of the piston rod 5, as shown in FIG. 6.

The present invention is applicable to any kind of apparatus requiring the particular actions of the device of this invention. However, musical instruments to which this invention can be applied include tuba, euphonium, fluegelhorn, piccolo-trumpet, horn, and other valved wind musical instruments.

As stated above, according to the valve assembly of the present invention, there is provided a slit in the lug member at the portion engaging a groove formed on the inner wall of the outer casing which receives the piston valve, and the gap of this slit can be widened by the use of a flush-headed screw or like means to thereby establish desirable perfect fit of the lug member in the lug member-receiving groove. Thus, it is possible to desirably completely eliminate an unnecessary play between the lug member and the lug member-receiving groove. Moreover, the arrangement according to this invention permits the prevention of undesirable noises to generate during the operation of the pis-

ton, and this contributes to an improvement in the effect of the music being played.

Also, the adjustment of the breadth of the groove engaging portion of the lug member relative to the lug member-receiving groove can be accomplished simply, only by the manipulation of the flush-headed screw or like means. Therefore, there can be greatly reduced the time which is required for the play-eliminating operation during the adjustment of the pistons. As such, the piston adjustment operation is greatly simplified and accomplished easily. Besides, in view of the fact that according to the present invention, there is not included any process of striking the lug member by a hammer, which has been done in the past. Accordingly, the manufactured valve assembly presents a good appearance of finish. Moreover, in case there develops an undesirable play again due to wear during an extended use of the piston valve, such a play can be corrected again quite easily in the manner as stated above.

I claim:

1. A valve assembly for use in a valved wind musical instrument, comprising a tubular outer casing having a groove extending longitudinally on the inner wall of the casing, a piston valve slidably and reciprocatingly housed in said outer casing, a lug member having a pair of abutting projections fitted in said groove, said projections assuming a distance therebetween and being

movable along the longitudinally extending groove, and means for securing said lug member to the piston valve and for adjustably varying the distance between said pair of projections.

5 2. A valve assembly according to claim 1, in which said lug member has a central bore passing therethrough and a slit joining at one end said bore and separating said pair of projections.

3. A valve assembly according to claim 1, in which 10 said valve has a recessed nest formed at a peripheral portion thereof and has a threaded bore passing through the nest, said lug member is received in said nest and has bifurcated projecting end portion providing said pair of projections fitted in the groove of said 15 tubular outer casing and defining therebetween a slit and has a central bore passing therethrough and joining said slit, and said means comprises a flush-headed screw passing through said bore of the lug member into the threaded bore of the nest.

20 4. A valve assembly according to claim 3, in which said bore of the lug member is outwardly flared for receiving said flush-headed portion of said screw.

5. A valve assembly according to claim 3, in which 25 said screw has a tapered side surface profile with a progressively reducing diameter as it goes from the head top toward the shank of this screw.
